UNITED STATES PATENT OFFICE

2,259,999

ANGLE ADAPTER

Frank D. Bryant, Stratford, and William R. Young, Fairfield, Conn., assignors to General Electric Company, a corporation of New York

Application September 27, 1939, Serial No. 296,786

14 Claims. (Cl. 173—324)

This invention relates to an adapter for electric lamps, or the like, and more particularly to an adapter which permits the lamp to be moved or focused to a variety of angular positions with respect to the support or socket in which the lamp is mounted.

It is an object of the invention to provide an adapter of the type described which permits a relatively large angular movement of the lamp and which is of a rugged construction such that it may be used to support a relatively heavy lamp, for example, a reflector lamp.

Another object of the invention is the provision of an adapter so constructed that a plurality of lamps, or like electrical devices, may be mounted thereon, each of which is movable through a variety of angular positions independently of the other.

In the accompanying drawings Fig. 1 is a view of the adapter with a reflector lamp mounted thereon; Fig. 2 is a sectional view through the adapter; Fig. 3 is another sectional view through the adapter taken along the lines 3—3 of Fig. 2; Fig. 4 is an exploded view of the elements of the adapter; Fig. 5 is a view of the adapter showing the range of angular adjustment in one plane; Fig. 6 is a similar view of the adapter showing the range of angular adjustment in another plane, and Fig. 7 is a view of the adapter provided with a plurality of supports or receptacles for a plurality of electric lamps, or the like.

Referring to the drawings, Fig. 1 shows an adapter 10 constructed in accordance with this invention and which supports an electric lamp 11, for example, a reflector lamp or spot light. The adapter comprises a plug member 12 supporting a ring-like member or annulus 13 on which is mounted a receptacle 14 for receiving the base of the lamp. The annulus is rotatably mounted on the plug member while the receptacle in turn is slidably along the periphery of the annulus. By providing these adjustments in two diverse planes of movement, it is possible to move the lamp to any one of a wide variety of angular positions relative to the support or socket into which the plug 12 is seated.

Turning to the construction of the adapter, the plug member 12 is formed with a base 15 of insulating material such as a molded plastic. At one end the base is provided with a threaded screw shell 16 held in position by an insulating disk 17 of porcelain, or the like, which, in turn, is mounted on the base by means of a centrally disposed rivet or drive pin 18. The rivet 18 forms the center contact of the plug base and cooper-

ates with the screw shell in providing contact means for engagement with a socket or receptacle into which the plug is to be mounted. In order to provide a mounting surface for the annulus 13, the upper portion of the plug 12 on the side opposite the center contact 18 is formed with a circular recess 19. A well 20 extends downwardly within the body of the plug base and is formed with a lateral slot 21 in the wall thereof. A shoulder 22 is formed at the junction of the circular recess 19 and well 20. The purpose of the well is to provide a suitable recess for the reception of the head of the drive pin or rivet 18 and, in addition, to provide a housing for a conducting pin 23 which is seated within an opening 24 in the head of the drive pin 18. A conducting strip 25 rests in the slot 21 and at one end is electrically connected to the screw shell 16. At the other end, the strip is formed with a bent-over bearing surface 26 for a purpose to be described later. The conducting pin 23 and conducting strip 25 are held in spaced relation within the well 20 by means of a disk of insulating material 27 which rests on the shoulder 22. To accomplish this purpose, the conducting pin 23 extends through an opening 28 centrally of the insulating plate, while the conducting strip 25 extends through a corresponding opening 29 which is formed in the outer edge of the plate in line with the slot 21. In order to hold the insulating plate securely in position on the shoulder 22, it is keyed into the base by means of a tang 30 which rests in a slot 31 formed in the wall of the recess 22. The conducting pin 23 and the conducting strip 25 form part of a means electrically to interconnect the contact elements of the plug base with the annulus 13 in a manner to be hereinafter described.

The annulus 13 comprises two ring-like members 32 of insulating material, for example, a molded plastic, and each one is provided with a recess 33 to receive the conducting rings or members 34 and 35. The inner edges 36 formed by the recesses 33 of the members 32 extend outwardly further than the outer edges 37 so that as the two insulating members are placed together the edges 36 are in engagement with each other, as shown at 38 in Fig. 3, while the outer edges are normally spaced apart from each other as shown at 39 in Figs. 3 and 6. The space 39 provides a path to the conducting rings 34 and 35 and makes it possible for the receptacle 14 to be electrically connected to the conducting rings in a manner to be described later. The annulus formed by mating of the insulating members 32

is provided in a portion of its periphery with a shoulder 40 having a curved surface 41 for mounting in the circular recess 19 of the plug base. A recess 42 is formed on the shoulder adjacent the curved surface 41 to receive two semi-circular locking rings or plates 43 which hold the annulus in position on the plug base. After assembly of the annulus upon the plug base the two locking rings 43 are simply slipped into the recess 42 and are then secured to the plug base by screws 44 which pass through openings 45 in the plug base into the complementary openings 46 in the locking plates. In this manner the annulus is securely held in position on the base and may be easily rotated thereon with the curved surface 41 resting in the recess 19, while the locking plates 43 are seated in the recess 42 and the edge of the shoulder resting upon the locking plates. As shown most clearly by Fig. 3, each of the locking plates 43 is provided with a recess 43' to receive a leaf spring 47 which takes up any play in these elements and insures a close fit between the locking plates and the shoulder on the annulus. The two parts of the annulus are provided with strengthening ribs 48 adjacent the shoulder 40 and these ribs are given a curved contour so that they streamline into the form of the plug base making a construction having a pleasing appearance.

In order to make electrical connection with the contact elements of the plug base, the conducting ring 34 is provided with an ear 49 having an opening 50 therein which receives a pointed end 51 of the conducting pin 23. Similarly, the conducting ring 35 is provided with an extending ear or bearing surface 52 which is adapted to engage a conducting ring 53, the latter being held in a recess 54 interiorly of the shoulder 40. The conducting ring 53 is assembled between the two parts of the annulus. An opening 55 in the ring 53 is made large enough so that the conducting pin 23 will extend therethrough without danger of making contact with the ring and the pin is retained in position by the guide jaws 55' extending from each half of the annulus. In this manner the conducting pin 23 is insulated from the conducting ring 53. In assembled position, the bearing surfaces 52 and 26 of the conducting ring 35 and the conducting strip 25, respectively, are in frictional engagement with the conducting ring 53 so that the conducting ring 35 is electrically connected to the conducting strip 25 and thereby the screw shell 16. As the annulus and conducting rings are rotated about the plug base, the bearing surface or ear 52 makes continuous contact with the conducting ring 53 and is therefore at all times in electrical connection with the screw shell 16; similarly, the ear 49 of the conducting ring 34 is at all times in contact with the conducting pin 23 and thereby the center contact 18, irrespective of the position to which the annulus has been rotated.

The receptacle 14 is provided with a two-part housing 56 made of insulating material, for example, a molded plastic, and the two parts of the housing are assembled together on each side of the annulus by means of any suitable fastening means, such as the bolt 57. Each of the insulating members of the annulus is slidable in a slot 58 formed in a corresponding half of the housing 56 so that the two parts of the annulus may be easily assembled within the slots upon the respective parts of the housing prior to assembly of these elements together. A curved

leaf spring 59 rests in a portion of the slots 58 and biases the annulus against the walls of the slots so that a frictional fit is obtained between these elements making it possible for the receptacle to be retained in any position to which it is moved and, at the same time, to provide for free angular movement of the receptacle around the periphery of the annulus. In order to make electrical connection with the base of the lamp, the receptacle is provided with a screw shell 60 having inturned edges 61 and the screw shell is mounted in a recess 62 formed in the insulating body 56 with the inturned edges 61 resting on the bottom of the recess. Holes 64 in the walls of the screw shell and corresponding projections 65 in the walls of the receptacle housing lock the screw shell in position and prevent it from being turned upon insertion of a lamp base. The screw shell is easily assembled in position due to the fact that the housing is made in two parts and may be assembled around the screw shell. A center contact 66 is disposed on the bottom of the recess 62 and is provided with a bent end 67 resting in a groove 68 formed in the wall of the housing. The center contact 66 is provided with a bearing surface 69 which makes slidable engagement with the conducting ring 34. In this manner the center contact 66 is electrically connected to the conducting ring 34 and through the medium of the conducting pin 23 to the center contact 18 of the plug base. Similarly, a conducting member or ear 70 is seated within a slot 71 in the wall of the recess and is provided with a bearing surface 72 adapted to engage one of the turned-in edges 61 of the screw shell. The other end of the conducting ear is provided with a bearing surface 73 adapted to engage the conducting ring 35. In this manner the screw shell 64 is placed in electrical engagement with the conducting ring 35 and through the medium of the conducting ring 35 and strip 25 with the screw shell 16. An insulating washer 74 having an opening 75 for receiving the center contact 66 is placed beneath the projecting abutments 65 and holds the screw shell 60 in mounted position on the receptacle body 56 and in tight frictional engagement with the bearing surface 72 of the conducting ear 70.

In assembling the device, the conducting rings are first placed within the recesses in the insulating members of the annulus and these members are placed around the conducting ring 53; the two-part receptacle housing is simultaneously assembled around the insulating members with the bearing surfaces 69 and 73 in engagement with the conducting rings. This assembly is then mounted on the plug base by means of the locking rings 43 with the ear 50 and conducting ring 53 making contact with the conducting pin 23 and conducting strip 25, respectively, in the manner indicated. In this way the receptacle 14 is electrically connected to the plug base. The two parts of the annulus are held together by the receptacle 14 and the locking rings 43.

It will be seen that the receptacle 14 may be moved around the periphery of the annulus to any angular position and the bearing elements 69 and 73 will at all times make contact with the conducting rings 34 and 35, so that the contact elements of the receptacle are continuously electrically connected to the contact elements of the plug base. The conducting members 67 and 70 move within the space 39 provided between the outer edges of the insulating elements of the annulus. Inasmuch as the conducting rings 34

and 35 are set back into the recesses of the insulating members, there is no danger of any accidental contact being made with them since they are well protected within the annulus.

Figs. 5 and 6 illustrate the wide range of angular movement through which the receptacle 14 may be moved relative to the plug base 12. It will be seen from an examination of Fig. 5 that the receptacle may be moved through an angle of approximately 180 degrees around the outer periphery of the annulus. Manifestly, the degree of angular movement may be increased by enlarging the annulus relative to the plug base so that the portion of the periphery which is used to attach the annulus to the plug base constitutes only a small portion of the total circumference of the annulus. It will likewise be apparent from an examination of Fig. 6 that the annulus and its attached receptacle may be rotated through an angle of 360 degrees. In fact, the annulus may be rotated continuously upon the plug base without in the least affecting its electrical connection with the plug base. This is of advantage because there are no wires or other connecting means to become twisted or dislocated by continuous rotation of these elements.

While the structure thus far described calls for a single receptacle to be mounted on the annulus, it should be manifest that a plurality of such receptacles may be mounted thereon, and that each one may be movable independently of the other and, yet, at the same time, will be in electrical connection with the plug base. Such an arrangement is shown in Fig. 7 in which two receptacles are illustrated as being mounted on the annulus. By increasing the diameter of the annulus to make room for the receptacle bodies the number to be mounted on the annulus may be increased at will. In this way each receptacle is movable independently of the other in a plurality of diverse planes.

What we claim as new and desire to secure by Letters Patent of the United States is:

1. In an adapter for electric lamps or the like, a plug base having contacts for electrical connection with an electric device, a substantially annular supporting member mounted on said base and having conducting portions electrically connected to said base contacts, and a plurality of receptacles slidably mounted on said member side by side, and each being electrically connected to said conducting portions, said receptacles being movable along said member independently of each other to various angular positions with respect to said base.

2. In an adapter, a plug base having contacts for electrical connection with an electric device, a substantially annular supporting member mounted on said base for rotation in a horizontal plane, said member having conducting portions electrically connected to said base contacts, and a plurality of receptacles slidably mounted on said member side by side and each being electrically connected to said conducting portions, said receptacles being movable along said member in a vertical plane to various angular positions with respect to said base.

3. In an adapter, a plug base having contacts for electrical connection with an electric device, an annulus mounted on said base in an upstanding position in a substantially vertical plane, said annulus being provided with conductors electrically connected to said plug contacts, and a receptacle slidably mounted on said annulus and being electrically connected to said conductors,

said receptacle being movable along the periphery of said annulus to any position through an angle of substantially 180 degrees in a vertical plane, said annulus being rotatably mounted on said base for rotation in a horizontal plane whereby said receptacle may be moved to any position through an angle of substantially 360 degrees.

4. In an adapter, a plug base having contacts for electrical connection with an electric device, an annulus mounted on said base in an upstanding position in a substantially vertical plane, said annulus being provided with conductors electrically connected to said plug contacts, and a plurality of receptacles each being slidably mounted on said annulus and each being electrically connected to said conductors, said receptacles being movable independently of each other along the periphery of said annulus to any position through an angle of substantially 180 degrees in a vertical plane, said annulus being rotatably mounted on said base for rotation in a horizontal plane whereby said receptacles may be moved simultaneously to any position through an angle of substantially 360 degrees.

5. In combination, a plug base having contact means for connection to an electrical device, an annulus rotatably mounted on said base for rotation in a horizontal plane, a plurality of conducting rings mounted in spaced relation on said annulus and being electrically connected to the contact means of said plug, and a receptacle slidably mounted on said annulus and having conducting members slidably engaging said

35 conducting rings.

6. In combination, a plug base having a screw shell and a center contact for connection to an electrical device, said base being provided with a recess, an annulus rotatably mounted on edge within said recess, a plurality of conducting rings mounted in spaced relation on said annulus, means electrically connecting said conducting rings to said screw shell contact and a receptacle slidably mounted on said annulus, said receptacle having a screw shell and center contact each being provided with slider elements in contact with said conducting rings.

7. In combination, a plug base having a screw shell and a center contact for connection to an electrical device, said base being provided with a recess on the side opposite said center contact, a two-part annulus rotatably mounted on a portion of its periphery within said recess, a conducting ring mounted in each part of said annulus, means electrically connecting said conducting rings to said screw shell and center contact, and a receptacle slidably mounted on said annulus, said receptacle having a screw shell and center contact each being provided with slider elements in contact with said conducting rings and moving in a space between the parts of said annulus.

8. In combination, a plug base having a screw shell and a center contact for connection to an electrical device, said base being provided with a circular recess on the side opposite said center contact, an annulus provided with a circular shoulder in a portion of the periphery thereof, said shoulder being seated in said recess for rotatably mounting said annulus on said plug base, a plurality of conducting rings mounted in spaced relation on said annulus, means electrically connecting said conducting rings to said screw shell and center contact, and a receptacle slidably mounted on said annulus, said recep-

tacle having a screw shell and center contact, each being provided with slider elements in contact with said conducting rings.

9. In combination, a plug base having contact means for connection to an electrical device, said base being provided with a circular recess, an annulus having a circular shoulder in a portion of the periphery thereof, said shoulder being seated in said recess for rotatably mounting said annulus on said base, a plurality of conducting rings insulated from one another and mounted on said annulus, means electrically connecting said conducting rings to the respective contact means of said plug base, and a receptacle slidably mounted on said annulus and being provided with slider elements in contact with said conducting rings for electrically interconnecting said receptacle and plug base.

10. In combination, a plug base having a screw shell and a center contact for connection to an electrical device, said base being provided with a circular recess therein, a two-part annulus provided with a circular shoulder in a portion of the periphery thereof, said shoulder being located in said recess rotatably to support said annulus on said base, a conducting ring mounted in each part of said annulus, means electrically connecting said conducting rings to said screw shell and center contact, and a receptacle slidably mounted on said annulus, said receptacle having a screw shell and center contact each being provided with slider elements in contact with said conducting ring and moving in a space between the parts of said annulus.

11. In combination, a plug base having contact means for connection to an electrical device, said base being provided with a circular recess therein, a two-part annulus provided with a shoulder in a portion of the periphery thereof, said shoulder being located in said recess rotatably to support said annulus on said base, a conducting ring mounted in each part of said annulus, means electrically connecting said conducting rings to said contact means, a two-part receptacle being joined together around the periphery of said annulus for slidable movement

thereon, said receptacle having a screw shell and center contact each being provided with slider elements in contact with said conducting rings and moving in a space between the parts of said annulus.

12. In combination, a plug base having a screw shell and a center contact for connection to an electrical device, said base being provided with a recess on the side opposite said center contact, an annulus rotatably mounted on edge within said recess, a plurality of conducting rings mounted on said annulus and being insulated from one another, each of said rings being provided with an ear extending into said recess, means engaging said ears and being electrically connected to said screw shell and center contact for placing said conducting rings in electrical connection with the screw shell and center contact irrespective of the degree of rotation of said annulus on said base, and a receptacle slidably mounted on said annulus and being provided with slider elements in contact with said conducting rings.

13. In an adapter for electric lamps, a fixed support having electrical conducting means mounted thereon, a substantially annular supporting member pivotally mounted on said support and having conducting elements electrically connected to said conducting means, and a receptacle slidably mounted on said annular member and being electrically connected to said supporting elements, said receptacle being movable along the perimeter of said annular member to various angular positions with respect to said fixed support.

14. In combination, a fixed support having electrical conducting means mounted thereon, an annulus rotatably mounted on said support for rotation in a horizontal plane, a plurality of conducting rings mounted in spaced relation on said annulus and being electrically connected to said conducting means, and a receptacle slidably mounted on said annulus and having conducting members slidably engaging said conducting rings.

FRANK D. BRYANT.
WILLIAM R. YOUNG.
